UNITED STATES PATENT OFFICE.

OTTO A. LEHMAN, OF HOBOKEN, NEW JERSEY.

DESIGN FOR AN APPAREL-BELT.

SPECIFICATION forming part of Design No. 35,794, dated March 4, 1902.

Application filed February 7, 1902. Serial No. 93,085. Term of patent 3½ years.

To all whom it may concern:

Be it known that I, OTTO A. LEHMAN, a citizen of the United States, and a resident of Hoboken, in the county of Hudson and State of New Jersey, have invented a new and original Design for an Apparel-Belt, of which the following is a specification, reference being had to the accompanying drawing, forming part thereof, in which the figure represents a face view of the apparel-belt embodying my design.

As shown in the drawing, the leading or material feature of my design consists in an apparel-belt having a general curved form from end to end, the lower edge presenting an irregular outline comprising a central blunt point 1, having concave edges 2 and 3 leading therefrom and convex edges 4 and 5 leading from the concave edges to the ends of the belt, and the upper edge presenting an irregular outline comprising a central sharp point 6 opposite the blunt point 1, said sharp point having concave edges developed

into convex edges 7 and 8 opposite the concave edges 2 and 3, and concave edges 9 and 10 opposite the convex edges 4 and 5, the face of the belt being ornamented by two figures formed by ribs raised from the surface of the belt, each figure comprising upper and lower ribs 11 and 12, following the contour of the belt for a distance along the same and joining each other at their outer ends, and a concave rib 13, connecting the inner ends of the upper and lower ribs.

What I claim is—

The design for an apparel-belt, substantially as herein shown and described.

In testimony that I claim the foregoing as my invention I have signed my name, in presence of two witnesses, this 1st day of February, A. D. 1902.

OTTO A. LEHMAN.
